UNITED STATES PATENT OFFICE.

DAVID HERSHCOWITZ AND JACOB BASS, OF NEWARK, NEW JERSEY.

DESIGN FOR A FINGER RING OR SIMILAR ARTICLE OF JEWELRY.

Application filed August 26, 1922. Serial No. 3,573. Term of patent 7 years.

To all whom it may concern:

Be it known that we, DAVID HERSHCOWITZ and JACOB BASS, citizens of the United States, residing at Newark, in the county of Essex and State of New Jersey, have invented a new, original, and ornamental Design for a Finger Ring or Similar Article of Jewelry, of which the following is a specification, reference being had to the accompanying drawing, forming part thereof.

Figure 1 is a side view,
Fig. 2 a top plan view, and
Fig. 3 an edge view of a ring embodying our new design.

We claim:

The ornamental design for a finger ring or similar article of jewelry.

DAVID HERSHCOWITZ.
JACOB BASS.
